CLAIM

The ornamental design for a microfiber booklet, as shown and described.

DESCRIPTION

FIG. 1 illustrates a perspective view of a microfiber booklet, showing our new design;

FIG. 2 illustrates a front elevation view thereof;

FIG. 3 illustrates a front elevation view of the microfiber booklet folded to an open position between a first microfiber sheet and a second microfiber sheet;

FIG. 4 illustrates a front elevation view of the microfiber booklet folded to an open position between the second microfiber sheet and a third microfiber sheet;

FIG. 5 illustrates a front elevation view of the microfiber booklet folded to an open position between the third microfiber sheet and a fourth microfiber sheet;

FIG. 6 illustrates a front elevation view of the microfiber booklet folded to an open position between the fourth microfiber sheet and a fifth microfiber sheet;

FIG. 7 illustrates a rear elevation view of the microfiber booklet folded to the open position between the second microfiber sheet and the third microfiber sheet;

FIG. 8 illustrates a rear elevation view of the microfiber booklet;

FIG. 9 illustrates a top plan view thereof;

FIG. 10 illustrates a bottom plan view thereof;

FIG. 11 illustrates a right side elevation view thereof; and, FIG. 12 illustrates a left side elevation view thereof.
